PROCESS FOR SEPARATING HYDROCARBON WAXES

August A. Schaerer, Orinda, Calif., assignor to Shell Development Company, Emeryville, Calif., a corporation of Delaware

Application May 20, 1952, Serial No. 288,790

12 Claims. (Cl. 196—17)

This invention relates to the art of separating hydrocarbon waxes. More particularly it pertains to the separation and recovery of various types of hydrocarbon waxes from mixtures thereof. Still more specifically, it pertains to the separation from waxy mineral oil stocks, including such stocks as contain a predominant proportion of paraffin wax such as of the character of slack wax and the like, of normal or straight-chain paraffin waxes contained therein, separately from non-straight chain or isomeric (iso- and cyclo-) paraffin waxes also contained therein.

Various methods have been used and suggested for the recovery and/or fractionation of paraffin waxes from mineral oil stocks. Thus, it is known to dewax waxy mineral oils or fractions thereof by cooling, sometimes after addition of a solvent and/or diluent. Dependent on the nature of the oil and the conditions of the operation, such as lowest cooling temperature, rate of cooling, manner of cooling, etc., the paraffin wax thus obtained has been either in the form of readily filterable crystals or of a poorly filterable, microcrystalline or amorphous product. The crystalline, readily filterable, products are usually obtained in connection with dewaxing operations as applied to paraffinic lubricating oil distillate stock and consist largely of high molecular weight aliphatic or paraffinic hydrocarbons with a straight chain, i. e. n-paraffins, whereas the microcrystalline or amorphous products consist, at least to a large and controlling extent, of high molecular weight aliphatic hydrocarbons of a branched character, including branched-chain and ring-containing hydrocarbons, generally termed isoparaffins and cycloparaffins, respectively, both classes of which may be termed as isomeric paraffins (relative to the n-paraffins). Frequently occurring cycloparaffins in mineral oils are paraffins having a naphthenic ring, generally of five or six carbon atoms per ring, to which is bound a straight or branched aliphatic hydrocarbon chain. Waxes obtained by the usual dewaxing operations, with or without the aid of solvents and/or diluents, generally contain appreciable proportions of oil. These waxes are usually de-oiled by a so-called sweating and filtering process and/or a solvent de-oiling process.

The n-paraffin hydrocarbon waxes on the one hand and the non-straight-chain paraffin hydrocarbon waxes on the other hand have properties which in many respects are widely divergent. These differences in properties account, for example, for the differences in applications or utility of the n-paraffin waxes and the isomeric paraffin waxes. Thus, for instance, normal paraffin waxes having at least 22 carbon atoms per molecule are particularly suitable for the manufacture of candles (candle wax) and paraffin paper, while the isomeric (iso- and cyclo-) paraffin waxes, especially those having more than approximately 26 carbon atoms per molecule, in an oil-free state, form useful products on account of their plastic properties and adhesion to glass and to metal articles.

In view of the differences in properties between straight chain or normal paraffin waxes on the one hand, and the isomeric paraffin waxes on the other hand, it is desirable and, therefore, an object of this invention to provide an improved process whereby they may be obtained from waxy petroleum stocks and separately from each other. A further object is to provide an improved process for the separation of n-paraffin waxes from iso- and/or cyclo-paraffin waxes and/or from oils in admixture therewith, and at the same time to separate the n-paraffin waxes into various fractions thereof approximating those of single molecular species. Another object of the invention is to

2

provide an improved process for dewaxing waxy oils and separating and recovering the waxes as desirable fractions of n-paraffinic waxes and of isomeric paraffinic waxes. Still another object is to provide an improved process for de-oiling oily waxes and separating and recovering the waxes as desirable fractions of n-paraffinic hydrocarbon waxes and of iso- and/or cyclo-paraffinic hydrocarbon waxes.

The foregoing objects will be better understood and others will become apparent from the following description of the invention, which will be made with reference to the accompanying drawing, wherein:

Fig. I is a graphical representation of the relationships between the boiling points, the melting points and the number of carbon atoms per molecule of paraffin hydrocarbons containing from 20 to 35 carbon atoms per molecule;

Fig. II shows graphically the solubility-temperature relationships of various normal paraffin wax hydrocarbons in methyl isobutyl ketone;

Fig. III shows graphically the solubility-temperature relationships in methyl ethyl ketone of three waxes having the same melting point, but having different molecular weights.

It has now been found that normal (i. e., straight-chain) paraffin waxes can be separated from other (i. e., iso- and cyclo-) paraffin waxes in mixtures thereof, particularly extending over the range of C₂₀ to C₃₅ hydrocarbons, by a combination of operations which comprises fractionating the given mixture into a number of fractions according to melting or freezing point, as by fractional crystallization, preferably in the presence of a solvent or diluent, at least one fraction of which has a relatively narrow melting point range (a range of about 4° C. to about 12° C.), and contains both straight-chain and non-straight-chain paraffins within that melting point range, the straight-chain hydrocarbons within that melting point range having a relatively small range of carbon atoms per molecule (3 to 4), and fractionating at least that fraction, according to molecular weight, under selected conditions, as by fractional distillation, or by fractional crystallization in the presence of such solvents as will permit crystallization of waxes according to molecular weights from hydrocarbon fractions having substantially the same melting point, to produce a first, lower molecular weight fraction of wax composed substantially entirely of at least a substantial portion up to substantially all of the straight-chain paraffin hydrocarbons present in the narrow melting point range fraction, and a second, higher molecular weight, fraction composed essentially of the non-straight-chain paraffin hydrocarbons. It is also contemplated to fractionate the second fraction according to molecular weight to separate the lower molecular weight non-straight-chain paraffin hydrocarbons present therein from higher molecular weight, non-straight-chain paraffins present.

In accordance with a preferred embodiment of the invention, the waxy mixture is fractionally crystallized, preferably in the presence of a solvent, into a plurality of fractions having narrow melting point ranges, respectively, and each fraction is then fractionally distilled to produce from each fraction a first, lower boiling point, lower molecular weight, fraction, composed substantially entirely of at least a substantial portion up to substantially all of the straight-chain paraffin hydrocarbons present in the particular fraction thus fractionated. Still further, the remaining portion of each fraction so fractionated can be fractionated to separate the lower boiling point, lower molecular weight non-straight-chain paraffin hydrocarbons present therein from the higher boiling point, higher molecular weight, non-straight-chain paraffins present, or any two or more of the remaining portions can be combined into one or more composite fractions of non-straight-chain hydrocarbons and then fractionated at a suitable temperature to separate iso- and cyclo-paraffinic hydrocarbons having boiling points below a selected boiling point from iso- and cyclo-paraffinic hydrocarbons having boiling points above that boiling point.

The invention is applicable to the separation of normal paraffin waxes from iso- and cyclo-paraffin waxes from mixtures composed for the most part of such waxes. It

is equally applicable to the separation of such waxes when they are present in oily wax mixtures thereof, such as oily waxes which have been separated from petroleum lubricating oil distillates or waxy deasphalted short residues by the usual lubricating oil dewaxing processes. The invention can also be used for the recovery and separation of normal paraffin waxes from iso- and cyclo-paraffin waxes, with or without subsequent separation and recovery of the iso- and cyclo-paraffin waxes, from highly paraffinic and paraffinic-naphthenic petroleum lubricating oil base stocks and distillates therefrom.

The present invention is based on the discovery that when a paraffinic petroleum waxy mixture of hydrocarbons is fractionated into narrow melting point fractions, that is, into fractions having a melting point range of about 4° C. to about 12° C., which fractionation can be effected by fractional crystallization of said mixture in a fluid state, either molten or dissolved in an organic solvent, the molecular weight of the highest molecular weight normal paraffin wax present in a given fraction is lower than the molecular weight of essentially all, if not all, of the isomeric paraffin waxes present, since the melting points of the paraffin waxes depend both on the molecular weight and on the molecular structure. The normal paraffins in each such fraction can then be readily separated as substantially pure normal paraffin waxes from the remainder of the fraction by fractionation according to molecular weight, for example, as by fractional distillation, since the boiling points of the normally solid paraffinic waxes depend primarily on the molecular weight thereof, or by fractional crystallization from such a solvent as will permit the crystallization of waxes according to molecular weights from hydrocarbon fractions having substantially the same melting point. The isomeric paraffin waxes remaining in the fractions can be separated into relatively lower molecular weight non-straight-chain hydrocarbons and relatively higher molecular weight non-straight-chain hydrocarbons. Alternatively, those fractions of isomeric paraffin waxes above a specified melting point can be combined, and all those below that melting point can also be combined.

The fractionation of the waxy mixture according to melting or freezing point can be effected by fractional crystallization, preferably in the presence of a suitable solvent or diluent. The fractionation of hydrocarbons according to melting or freezing points will be understood more readily by reference to the graphical representations of the melting point relationships shown in Figure I. The melting points of paraffin hydrocarbons are strongly dependent on the structures of the hydrocarbons. This appears to be true particularly in the case of structurally different paraffin wax hydrocarbons, that is, paraffinic hydrocarbons containing about 16 or more carbon atoms per molecule, and especially those containing at least about 20 carbon atoms per molecule. Either branching or ring-closure within an aliphatic (paraffin) hydrocarbon of the ranges indicated is accompanied by a marked and significant drop in the melting point. It has been found that the melting point of a given n-paraffin wax hydrocarbon containing n carbon atoms per molecule (n being at least about 16 and preferably 20 or more) is still significantly higher than the melting points of the non-straight-chain wax hydrocarbons containing $n+3$, and even $n+4$, carbon atoms per molecule. At a given melting point, then, there is a considerable difference between the molecular weights of the straight-chain wax hydrocarbons and non-straight-chain wax hydrocarbons melting thereat. This is more readily seen from the portion of Figure I which shows the relationships between the melting points (as ordinates reading on the left side of the figure) and the number of carbon atoms per molecule (along the horizontal axis). The melting points for the straight-chain paraffin hydrocarbons are represented by the indicated solid curve, which is approximated by the indicated straight dashed line, corresponding to the linear equation:

Melting point (° C.) = $-7.5 + 2.4 n$, for integral values of n from about 20 to about 36, and wherein n is the number of carbon atoms per molecule of the straight-chain paraffinic hydrocarbon. Thus there is a change of about 2.4° C. in melting point for a change of one carbon atom per molecule.

Whereas there is only a single normal paraffin hydrocarbon having the formula C_nH_{2n+2} for a given value of n , there are many isomeric branched-chain and cyclo-

paraffinic hydrocarbons having the same number of carbon atoms per molecule. The x points in Figure I are indicative of the melting points of such isomeric paraffins, the melting points of still many others of said isomers being below 16° C., the lowest point representable on the graph.

It will be seen from the foregoing, and by reference to Figure I, that a sharply cut, narrow melting point fraction of paraffinic hydrocarbons having an average melting point within the range of about 16° C. to about 76° C., and having a melting range of not over about 12° C., will define a mixture of paraffinic hydrocarbons containing as normal paraffinic hydrocarbons substantially only those which come within a carbon atom range of four and as isoparaffinic hydrocarbons those containing a greater number of carbon atoms than the highest molecular weight normal paraffin present. Similarly for mixtures of still higher melting paraffin waxes. Thus, a melting point fraction having a melting range of from about 51° C. to about 61° C., contains as normal paraffinic hydrocarbons only those which contain 24 to 28 carbon atoms per molecule, while containing essentially only isoparaffinic hydrocarbons which contain at least 31 carbon atoms per molecule. From the foregoing, it will be understood, for example, that when it is desired to obtain a melting point fraction of paraffinic hydrocarbons containing as the highest molecular weight normal-paraffin, n -C₂₈H₅₈, in any substantial amount, the fraction will have an initial melting point of about or only a small amount above the melting point of the n-C₂₈ paraffin, that is about 61° C., and the end melting point will be lower than 61° C. by a value of about 2.4 multiplied by n , n being the carbon atom range of the desired fraction. Thus, if the range is to be two carbon atoms, then the temperature range is about twice 2.4, or about 5° C.; for a three carbon atom range, the temperature range is about 3 times 2.4, or 7.2, or from about 7° to about 8° C.; and not more than about 9° C., and for a four carbon atom range, the temperature range is about 4 times 2.4, or 9.6, or from about 9° to about 10° C., and not over about 12° C.

It is preferred to fractionate the waxy paraffinic hydrocarbon mixture into narrow melting range fractions, in the presence of a suitable solvent or diluent, particularly one which is not a preferential solvent for the n-paraffins or for the non-straight-chain paraffins. The solubility of a paraffin wax hydrocarbon in a solvent, for example, a polar solvent, such as oxygenated and/or halogenated hydrocarbon derivatives (methyl isobutyl ketone, carbon tetrachloride, ethylene dichloride), and mixtures thereof, and also in admixture with hydrocarbons such as benzene, toluene, light petroleum hydrocarbons, and the like, becomes exceedingly low at a given temperature below the solidification or melting point of the paraffin hydrocarbon, the given temperature being dependent upon and correlated with the melting point of the paraffin hydrocarbon and being substantially independent of the structural configuration of the paraffin. The respective solidification temperature of the different waxes are, of course, lowered below their melting points because of the solvency of the solvent. In general, in practical operations, wherein 2 to 10, and preferably 5 to 7, volumes of solvent are employed per weight of oil and/or wax, using consistent units in the c. g. s. system, as cubic centimeters of liquid per gram of solid, a temperature of 30° to 40° C. below the melting point of a given paraffin wax species insures almost complete insolubility of that given wax.

In order to show how well a wax mixture may be separated by fractional crystallization, a blend of equal parts of three practically pure normal paraffin hydrocarbons was fractionally crystallized from methyl isobutyl ketone. The hydrocarbons used were: (1) Normal C₂₂H₄₆—M. P.=45° C.; (2) Normal C₂₆H₅₄—M. P.=56° C.; and (3) Normal C₃₀H₆₂—M. P.=65.2° C.; their individual solubility curves in methyl isobutyl ketone are shown in Figure II. One part by weight of this blend was dissolved in 9 parts by weight of methyl isobutyl ketone and then very slowly cooled. The first wax crystals appeared at 39° C., which is exactly the temperature at which the pure C₃₀H₆₂ would start to crystallize if it were alone in solution (as a 3.3% solution). With stirring, the wax slurry was cooled to 28° C. and then quickly filtered through a precooled Buchner funnel (28° C. is approximately the temperature at which the C₂₆H₅₄

wax would start to crystallize if it were alone in the solution). The wax cake was washed on the funnel with 3.3 parts (precooled) methyl isobutyl ketone, firmly pressed, and finally freed from solvent in a porcelain dish. The filtrate was cooled further to 15° C. (the saturation temperature of *n*-C₂₂H₄₆), filtered and again washed with 3.3 parts of solvent. After removing the solvent from both the cakes and the final filtrate, the following waxes were obtained:

	Filter temp., ° C.	Wax, pts.	Wax, M. P., C.
Fraction 1	28	0.32	64.4
Fraction 2	15	0.30	56
Fraction 3	(1)	0.38	45.8

¹ Filtrate.

The fractionation of the narrow melting range paraffinic waxy petroleum fractions into wax products according to molecular weight, as by fractional distillation, to separate substantially pure normal paraffin waxes from the non-straight chain paraffinic hydrocarbons, and the coordinated combination thereof with the fractionation according to melting points, will be more fully understood from the following description made with particular reference to the boiling point relationships shown in Figure I. The upper curve (normal paraffins) in Figure I was constructed from the boiling points of the normal paraffin hydrocarbons having from 19 to 36 carbon atoms per molecule. The next solid curve thereunder represents the boiling point-carbon atom per molecule relationship for all paraffinic hydrocarbons, the boiling points being averaged for all paraffins having a given carbon-atom-per-molecule content. The boiling points represented on both these boiling point curves are at 15 mm. of mercury pressure. The numerical values for the boiling points of the paraffins and for the melting points of the straight-chain paraffins, from which the curves were constructed, were taken from "Physical Constants of the Principal Hydrocarbons," by M. P. Doss, 4th edition, 1943, and "Physical Constants of Hydrocarbons," by E. Egloff, A. C. S. Monograph Series No. 78, vol. II, 1940. Conversions of boiling points from reported values to 15 mm. of Hg pressure, where the reported value was for a different pressure, were made by utilizing the conversion chart given by Watson and Wirth, in Ind. and Eng. Chem., Anal. Ed., vol. 7, page 73, January 1935.

The upper dashed line in Fig. I is a straight line with a slope of about 8.53° C. (at 15 mm. Hg) per unit carbon-atom-per-molecule change and, as is readily seen, represents within about 2° C. the boiling points of the normal paraffins from C₂₀ to C₃₆, and also represents within from about 2° C. to about 5° C. the boiling points of substantially all of the paraffinic hydrocarbons from C₂₀ to C₃₆. As indicated in Fig. I, this relationship is expressed by the equation:

$$\text{Boiling point (° C. at 15 mm. of Hg)} = 36 + 8.53 n$$

for integral values of *n* from about 20 to about 36, and wherein *n* is the number of carbon atoms per molecule of the paraffinic hydrocarbon. According to the dashed line and the equation, there is a change in boiling points, of paraffinic hydrocarbons having from about 20 to about 36 carbon atoms per molecule, at 15 mm. of Hg pressure, of about 8.5° C. (15.3° F.) for each unit change in carbon atoms per molecule of the paraffin hydrocarbon. For other pressures the boiling temperatures are changed for the respective hydrocarbons, as may be readily determined by use of the already indicated conversion method of Watson and Wirth, although the change in boiling temperatures with change in carbon atom per molecule content at a given pressure remains substantially the same, namely about 8.5° C. per unit change in carbon atoms per molecule. Thus, the boiling temperature converted to 760 mm. of Hg (atmospheric pressure), of *n*-C₂₆H₅₄ is about 422° C. and of *n*-C₃₀H₆₂ is about 462° C., the difference being about 40° C. for the C₂₆ to C₃₀ range, a carbon atom range of four, or about 10° C. per carbon atom difference.

In the graph in Figure I, various fractions are defined by horizontal dotted lines. Each of the fractions so defined covers approximately a melting point range of

about 8° C. Each fraction also covers a range of not more than about 4 carbon atoms per molecule of the normal paraffinic hydrocarbons contained therein. Referring to the graph, it is seen, for example, that the normal paraffinic hydrocarbon having a melting point of about 48° C. contains fewer carbon atoms per molecule and has a lower boiling point than the lowest molecular weight and lowest boiling non-straight chain paraffin hydrocarbon isomer (i. e., iso- or cyclo-paraffin hydrocarbon) having a melting point of 40° C. or even 38° C. It will be further noted from the graph that there are many more isomeric iso- and cyclo-paraffins melting between about 40° C. and 48° C. which contain a still greater number of carbon atoms per molecule and have a still higher boiling point than the normal paraffin hydrocarbon melting at 48° C. These other isomeric paraffins constitute a large proportion of the total isomeric paraffin content of any actual petroleum distillate fraction of a petroleum oil stock containing both normal and isomeric paraffin hydrocarbons.

Although the above-indicated differences in molecular weights of paraffin wax hydrocarbons having melting points within a relatively narrow melting range make it possible to separate such mixtures of paraffin wax hydrocarbons by a process of fractional distillation, based on boiling point differences, it is also possible to separate such mixtures by a process of recrystallization from a solvent which permits the crystallization of waxes according to molecular weight from hydrocarbon fractions having substantially the same melting points. The solubility of a paraffin wax hydrocarbon in a solvent, for example, a polar solvent such as methyl ethyl ketone, is related to the molecular weight of the paraffin hydrocarbon, the lowest molecular weight paraffin hydrocarbon being the most soluble in the solvent at a given temperature. The effect of the presence of methyl ethyl ketone on the solidification temperatures of representative straight-chain paraffin waxes and non-straight-chain paraffin waxes having the same melting point but different molecular weights. Referring to Fig. III, A is a normal paraffin hydrocarbon wax having a molecular weight of 282; B is a non-straight-chain paraffin wax having a molecular weight of 490; and C is a non-straight-chain paraffin wax having a molecular weight of 540. Each of the waxes has a melting point of 36° C. The solubilities of each wax in methyl ethyl ketone at various temperatures are shown by the indicated curves.

Having described the invention in a general manner and having discussed various factors related to the invention, and their correlation in the application of the invention, it will be better understood from a more detailed description of a more specific embodiment thereof. A more detailed description will be made with reference, for example, to a so-called "slack" wax or "crude" wax, produced and obtained in the art and which is usually an oily mass of a mixture predominating in paraffin waxes, including both *n*-paraffins and iso- and cyclo-paraffins, the proportions thereof depending on the nature of the petroleum stock from which the slack wax is obtained. A representative total lubricating oil distillate slack wax may have a boiling range of from about 180° C. to about 310° C. at 7 mm. of Hg pressure, corresponding to from about 200° C. to about 330° C. at 15 mm. of Hg pressure, and may have a range for the number of carbon atoms per molecule of C₂₀ to C₃₅ or C₃₆ and generally will contain from about 40% to about 80% of wax and 20% to 60% of oil, the melting point of the wax ranging from about 90° F. to about 165° F., depending on the relative proportions of wax and oil and also on the relative proportions of the various molecular species of wax molecules present.

Now, the first essential step, in accordance with the present invention, is to fractionate the slack wax into a number of narrow melting range fractions, at least one fraction of which, and preferably all fractions, containing paraffin hydrocarbon waxes such that the molecular weight of the lowest molecular weight isomeric paraffin wax in said fraction is higher than the highest molecular weight of the lowest molecular weight isomeric paraffin wax in each such fraction having a range of carbon atoms per molecule of not more than four and preferably not more than two or three. In general, it will be satisfactory if at least 90% of the isomeric paraffin waxes there-in has a higher molecular weight than the highest molec-

ular weight n-paraffin wax present. The separation of the wax content of the slack wax into the indicated fractions may be effected either with or without a prior separation of any or a substantial proportion of the oil content thereof.

That is, the slack wax may be de-oiled by any suitable method, such as sweating and/or solvent de-oiling, first to remove substantially all or a substantial proportion of the oil content thereof, to produce a scale wax and the separated wax then fractionated, as by fractional crystallization, into the desired fractions. It will also be understood that the total lubricating oil distillate stock can be dewaxed at successively lower temperatures, with separation of wax from oil at each dewaxing temperature, to obtain the desired fractions.

The fractionation of the slack wax into narrow melting range fractions is preferably effected by fractional crystallization in the presence of a suitable solvent or diluent. Suitable diluents include lighter petroleum fractions, such as kerosene, gasoline, naphtha, propane, butane, etc., fractions, as well as various organic liquids such as halogenated hydrocarbons (chloroform, carbon tetrachloride, ethylene dichloride, ethylidene dichloride, etc.), ethers (ethyl ether, ethyl propyl ether, methyl isobutyl ether, and the like), ketones (acetone, methyl isobutyl ketone, etc.), aromatic hydrocarbons (benzene, toluene, xylene, and the like), and various mixtures thereof.

After having adjusted the temperature of the slack wax to solidify a narrow melting range wax fraction, the resulting mixture or slurry is separated, as by filtration or centrifugation or the like into a separated solid fraction having a narrow melting range and a separated liquid fraction containing the lower melting constituents.

Now, assuming for clarity of discussion that the slack wax has been fractionated to produce at least one narrow melting range slack wax fraction as defined above, the next essential step of the process is to separate the relatively lower molecular weight (i. e., lower boiling) normal paraffin hydrocarbons therein from the relatively higher molecular weight (i. e., higher boiling) isomeric paraffin hydrocarbons therein. The desired separation is preferably effected by fractionally distilling the indicated fraction at a temperature between the boiling point of the highest molecular weight (i. e., highest boiling) normal paraffin wax therein and the lowest molecular weight (i. e., lowest boiling) isomeric paraffin wax therein thereby removing all or substantially all of the normal paraffin waxes as distillate. The remaining liquid fraction can be further separated at a still higher temperature to separate the relatively lower molecular weight isomeric paraffin waxes from the relatively higher molecular weight isomeric paraffin waxes.

It will be understood, particularly by reference to Fig. I, that a substantial separation, which may be entirely satisfactory in some cases, depending on the initial wax material, the desired wax products, etc., may be accomplished by minor deviations from the above indicated combination of operations. For example, in some cases the composition of a given fraction may be such that the temperature of separation of the straight-chain and non-straight-chain paraffin waxes may actually be below the boiling point of the highest boiling normal paraffin wax present, and still satisfactory products will be obtained. Conversely, in some cases the temperature of separation may be above the boiling point of the lowest boiling non-straight-chain paraffin wax. Similarly, as will be seen from Fig. I, slightly wider range fractions may be resolved into satisfactory straight-chain and non-straight chain paraffin wax products by application of the invention, even in those cases where the molecular weight of the highest molecular weight normal paraffin wax is not necessarily below the molecular weight of the lowest molecular weight non-straight-chain paraffin wax present, provided the resulting "overlapping" of molecular weights does not involve more than about 10%, preferably not more than 5%, of the total paraffin wax content of the fraction involved, or not more than about 10% based on the normal paraffin wax content thereof. Thus, in general, the selection of a range of the paraffin wax hydrocarbons for a given fraction and/or the selection of a suitable temperature for separation of the normal- from the isomeric-paraffin waxes therein are correlated so that the paraffin wax content of one of the separated products will be such that the ratio of the

weight of one of the types of paraffin waxes therein to the other type will be at least about 90 to 10, that is, 90% purity on the wax basis with respect to either the normal- or the isomeric-paraffin wax.

The present invention is applicable to the treatment of various types of paraffinic wax mixtures, including slack waxes (as described above), slop waxes, scale waxes, short and long wax residues as obtained by processes well known to the art, etc. The fractionation of the wax mixture into the required fractions to be processed in accordance with the invention may be made by any suitable method, such as by fractional crystallization, and in the absence or presence of a suitable solvent or diluent. In the fractionation, sufficiently narrow range of melting points in a cut may be tested empirically by a small-scale test on an aliquot part of the "cut" to determine that, when the resulting solution is heated appreciably above the boiling point of the highest boiling n-paraffin wax therein, there is substantially complete separation of the n-paraffin wax therein from the non-straight-chain waxes in the cut. Tests upon the resulting separated wax to show the structural character of the wax are readily made by persons skilled in the art making use of such conventional tests as that for ring value and for asymmetric value.

Various modifications of the hereinabove-described techniques of manipulation as are known in the art may be utilized in the practice of the invention. Thus, the separation of solid from liquid phases may be effected by pressure filtration, vacuum filtration, centrifugation, etc. The cooling operations effecting wax crystallization may be stepwise, if desired, and also with or without "shock" chilling with stepwise introduction of super-cooled diluent and/or selective solvent so as to effect a control over the crystal formation.

I claim as my invention:

1. A process for the separation of straight-chain paraffin waxes from paraffinic waxy mixtures comprising both straight-chain paraffin waxes and non-straight-chain paraffin waxes and wherein there is an overlapping of the melting points of the two types of waxes present, which process comprises the steps of: separating from said waxy mixture by crystallization a plurality of narrow melting range fractions at least one of which contains both straight-chain and non-straight-chain paraffin waxes and has a melting point range of not more than about 12° C., whereby the boiling point of the highest boiling straight-chain paraffin wax present is lower than the boiling point of the lowest boiling non-straight-chain paraffin wax present therein; and separating said fraction by distillation into a first relatively lower boiling, lower molecular weight fraction composed substantially entirely of the straight-chain paraffin waxes present in said fraction, and a second relatively higher boiling, higher molecular weight fraction composed substantially entirely of the non-straight-chain paraffin waxes present therein.

2. A process for the separation of straight-chain paraffin waxes from paraffinic waxy mixtures comprising both straight-chain paraffin waxes and non-straight-chain paraffin waxes and wherein there is an overlapping of the melting points of the two types of waxes present, which process comprises the steps of intimately mixing said waxy mixture with a non-viscous diluent which is non-reactive therewith; separating from the resulting mixture by crystallization a plurality of fractions each of which has a melting point range of not more than about 12° C., and contains both straight-chain paraffin waxes and non-straight-chain paraffin waxes, whereby the boiling point of the highest boiling straight-chain paraffin wax present in a given one of said fractions is lower than the boiling point of the lowest boiling non-straight-chain paraffin wax present; and separating each of said fractions by distillation into a first relatively lower boiling, lower molecular weight fraction composed substantially entirely of the straight-chain paraffin waxes present in said fraction, and a second relatively higher boiling, higher molecular weight fraction composed substantially of the non-straight-chain paraffin waxes present therein.

3. A process for the separation of straight-chain paraffin waxes from paraffinic waxy mixtures containing both straight-chain paraffin waxes and non-straight-chain paraffin waxes ranging from about C_{20} to about C_{35} and wherein there is an overlapping of the boiling points of the two types of waxes present, which comprises the steps of: separating from said waxy mixture by crystallization

a plurality of narrow melting range fractions at least one of which has a melting point range of not more than about 12° C. and contains both straight-chain and non-straight-chain paraffin waxes, the number of carbon atoms per molecule of the straight-chain paraffin waxes therein differing by not more than four carbon atoms, whereby the boiling point of the highest molecular weight straight-chain paraffin wax present is lower than the boiling point of the lowest molecular weight non-straight-chain paraffin wax present therein; separating said fraction by distillation into a first relatively lower boiling, lower molecular weight fraction composed of substantially all of the straight-chain paraffin waxes therein and a second relatively higher boiling, higher molecular weight fraction composed of substantially all of the non-straight-chain paraffin waxes therein; and further separating by distillation said second relatively higher boiling fraction composed of substantially all of the non-straight-chain paraffin waxes therein into a first fraction composed of relatively lower boiling, lower molecular weight non-straight-chain paraffin waxes and a second fraction composed of relatively higher boiling, higher molecular weight non-straight-chain paraffin waxes.

4. A process for the separation of straight-chain paraffin waxes from paraffinic waxy mixtures containing both straight-chain paraffin waxes and non-straight-chain paraffin waxes ranging from about C_{20} to about C_{35} and wherein there is an overlapping of the boiling points of the two types of waxes present, which comprises the steps of: intimately mixing said waxy mixture with a non-viscous diluent which is non-reactive therewith, separating from the resulting mixture by fractional crystallization a plurality of fractions at least one of which has a melting range of not more than about 9° C. and contains both straight-chain and non-straight-chain paraffin waxes, the number of carbon atoms of the straight-chain paraffin waxes therein differing by not more than three carbon atoms, whereby the boiling point of the highest molecular weight straight-chain paraffin wax is lower than the boiling point of the lowest molecular weight non-straight-chain paraffin wax present therein; and separating said fraction by distillation into a first relatively lower boiling fraction composed of substantially all of the straight-chain paraffin waxes therein and a second relatively higher boiling fraction composed of substantially all of the non-straight-chain paraffin waxes therein.

5. A process for the separation of straight-chain paraffin waxes from non-straight-chain paraffin waxes in an oily slack wax stock having a boiling range of from about 180° C. to about 310° C. at 7 mm. of Hg pressure and containing paraffinic waxes ranging from about C_{20} to about C_{35} , which process comprises intimately mixing said slack wax with a non-viscous diluent non-reactive therewith; separating from the resulting mixture by fractional crystallization a plurality of narrow melting range fractions at least one of which has a melting point range of not more than about 12° C. and contains both straight-chain and non-straight-chain hydrocarbon waxes, the number of carbon atoms per molecule of said straight-chain hydrocarbon waxes therein differing by not more than four carbon atoms, whereby the molecular weight of the highest molecular weight straight-chain wax is lower than the molecular weight of the lowest molecular weight non-straight-chain paraffin wax present therein; and separating said fraction by distillation into a first relatively lower boiling fraction composed of substantially all of the straight-chain paraffin waxes therein and a second relatively higher boiling fraction composed of substantially all of the non-straight-chain paraffin waxes therein.

6. A process for the separation of straight-chain paraffin waxes from paraffinic waxy mixtures containing both straight-chain paraffin waxes and non-straight-chain paraffin waxes ranging from about C_{20} to about C_{35} and wherein there is an overlapping of the melting points of the two types of waxes present, which comprises the steps of: separating from said mixture by fractional crystallization a plurality of fractions at least two of which have a melting range of not more than about 12° C. and contain both straight-chain and non-straight-chain paraffin waxes, whereby the boiling point of the highest molecular weight straight-chain paraffin wax is lower than the boiling point of the lowest molecular weight non-straight-chain paraffin wax present therein; separating each of said fractions by distillation into a first relatively lower boiling, lower

molecular weight fraction composed of substantially all of the straight-chain paraffin waxes therein and a second relatively higher boiling, higher molecular weight fraction composed of substantially all of the non-straight-chain paraffin waxes therein; combining at least substantial proportions of the separated relatively higher boiling fractions; and separating the resulting mixture by distillation into a first fraction composed of relatively lower boiling, lower molecular weight non-straight-chain paraffin waxes and a second fraction composed of relatively higher boiling, higher molecular weight non-straight-chain paraffin waxes.

7. A process for the separation of straight-chain paraffin waxes from paraffinic waxy mixture comprising both straight-chain paraffin waxes and non-straight-chain paraffin waxes and wherein there is an overlapping of the melting points of the two types of waxes present, which process comprises the steps of: separating from said waxy mixture by crystallization a plurality of narrow melting range fractions at least one of which contains both straight-chain and non-straight-chain paraffin waxes and has a melting point range of not more than about 12° C., whereby the molecular weight of the highest molecular weight straight-chain paraffin wax present is lower than the molecular weight of the lowest molecular weight non-straight-chain paraffin wax present therein; and separating said fraction into a first relatively lower molecular weight fraction composed substantially entirely of the straight-chain paraffin waxes present in said fraction, and a second relatively higher molecular weight fraction composed substantially entirely of the non-straight-chain paraffin waxes present therein.

8. In a process for dewaxing a waxy mineral oil which contains both n-paraffin hydrocarbon waxes and isomers thereof extending over the range of C_{20} to C_{35} hydrocarbons, and wherein there is an overlapping of the melting points of the two different types of waxes present, the improvement which comprises the steps of: intimately mixing said waxy mineral oil with an oil-miscible organic polar solvent which is substantially immiscible with solid wax at dewaxing temperatures; separating from the resulting oil-solvent mixture by dewaxing at successively decreasing temperatures a plurality of narrow melting range fractions at least one of which has a melting point range of not over about 12° C. and contains both straight-chain and non-straight-chain paraffin hydrocarbon waxes, whereby the molecular weight of the highest molecular weight straight-chain paraffin wax present is lower than the lowest molecular weight non-straight-chain paraffin wax present; and separating said fraction by distillation into a first relatively lower boiling fraction composed of substantially all of the straight-chain paraffin waxes therein and a second relatively higher boiling fraction composed of substantially all of the non-straight-chain paraffin waxes therein.

9. In a process for dewaxing a waxy mineral oil which contains both n-paraffin hydrocarbon waxes and isomers thereof extending over the range of C_{20} to C_{35} hydrocarbons, and wherein there is an overlapping of the melting points of the two different types of waxes present, the improvement which comprises the steps of: intimately mixing said waxy mineral oil with an oil-miscible organic polar solvent which is substantially immiscible with solid wax at dewaxing temperatures; separating from the resulting oil-solvent mixture by dewaxing at successively decreasing temperatures a plurality of narrow melting range fractions at least one of which has a melting point range of not over about 9° C. and contains both straight-chain and non-straight-chain paraffin hydrocarbon waxes, the number of carbon atoms per molecule of the straight-chain paraffin hydrocarbon waxes differing by not more than three carbon atoms, whereby the molecular weight of the highest molecular weight straight-chain paraffin wax present is lower than the lowest molecular weight non-straight-paraffin wax present; and separating said fraction by distillation into a first relatively lower boiling, lower molecular weight fraction composed of substantially all of the straight-chain paraffin waxes therein and a second relatively higher boiling, higher molecular weight fraction composed of substantially all of the non-straight-chain paraffin waxes therein.

10. In a process for dewaxing a waxy mineral oil which contains both n-paraffin hydrocarbon waxes and isomers thereof extending over the range of C_{20} to C_{35} hydrocar-

bons, and wherein there is an overlapping of the melting points of the two different types of waxes present, the improvement which comprises the steps of: intimately mixing said waxy mineral oil with an oil-miscible organic polar solvent which is substantially immiscible with solid wax at dewaxing temperatures; separating from the resulting oil-solvent mixture by dewaxing at successively decreasing temperatures a plurality of narrow melting range fractions at least one of which has a melting point range of not over about 12° C. and contains both straight-chain and non-straight-chain paraffin hydrocarbon waxes, whereby the molecular weight of the highest molecular weight straight-chain paraffin wax present is lower than the lowest molecular weight non-straight-chain paraffin wax present; and separating said fraction by distillation into a first relatively lower boiling fraction composed of substantially all of the straight-chain paraffin waxes therein and a second relatively higher boiling fraction composed of substantially all of the non-straight-chain paraffin waxes therein, and further separating by distillation said second relatively higher boiling fraction into a first fraction composed of relatively lower boiling, lower molecular weight non-straight-chain paraffin waxes and a second fraction composed of relatively higher boiling, higher molecular weight non-straight-chain paraffin waxes.

11. In a process for dewaxing a waxy mineral oil which contains both n-paraffin hydrocarbon waxes and isomers thereof, and wherein there is an overlapping of the melting points of the two different types of waxes present, the improvement which comprises the steps of: separating from said waxy mineral oil by dewaxing at successively decreasing temperatures a plurality of narrow melting range fractions at least one of which has a melting point range of not over about 12° C. and contains both straight-chain and non-straight-chain paraffin hydrocarbon waxes, whereby the molecular weight of the highest molecular

weight straight-chain paraffin wax present is lower than the lowest molecular weight non-straight-chain paraffin wax present; and separating said fraction by distillation into a first relatively lower boiling, lower molecular weight fraction composed of substantially all of the straight-chain paraffin waxes therein and a second relatively higher boiling, higher molecular weight fraction composed of substantially all of the non-straight-chain paraffin waxes therein.

10 12. A process for dewaxing a waxy mineral oil which contains both n-paraffin hydrocarbon waxes and isomers thereof, and wherein there is an overlapping of the melting points of the two different types of waxes present, the improvement which comprises the steps of: separating from said waxy mineral oil by dewaxing at successively decreasing temperatures a plurality of narrow melting range fractions at least one of which has a melting point range of not over about 12° C. and contains both straight-chain and non-straight-chain paraffin hydrocarbon waxes, whereby the molecular weight of the highest molecular weight straight-chain paraffin wax present is lower than the lowest molecular weight non-straight-chain paraffin wax present; and separating said fraction into a first relatively lower molecular weight fraction composed of substantially all of the straight-chain paraffin waxes therein and a second relatively higher molecular weight fraction composed of substantially all of the non-straight-chain paraffin waxes therein.
